United States Patent Office

Des. 183,645
Patented Oct. 7, 1958

183,645

RAILING UNIT

Louis Blum, Pittsburgh, Pa.

Application November 3, 1955, Serial No. 38,708

Term of patent 14 years

(Cl. D13—7)

Fig. 1

Fig. 1 is a rear perspective view of a railing unit showing my new design;

Fig. 2 is a front perspective view thereof; and

Fig. 3 is a cross-sectional view taken in the direction of line 3—3 of Fig. 2.

I claim:

The ornamental design for a railing unit, as shown.
